UNITED STATES PATENT OFFICE.

EUGENE E. EDENHARDER AND JACOB E. EDENHARDER, OF WEST ALLIS, WISCONSIN,
ASSIGNORS OF ONE-THIRD TO HELEN EDENHARDER, OF WEST ALLIS, WISCONSIN.

BOTTLE-WASHING ATTACHMENT.

Application filed April 30, 1928. Serial No. 105,708.

Our invention relates to a portable bottle washing device, primarily designed for domestic use, and which may be quickly attached to the water supply in any building.

5 It comprises a horizontally disposed cleaning brush arranged for rotation, over which the bottle to be cleaned may be slipped.

It comprises also the provision of a duct 10 for conveying water to the inside of the bottle under the full pressure of the main, whereby such pressure causes the water to flow with a force which is unusual in devices of this class.

15 It further comprises an operating mechanism, whereby through multiplying gears, rapid rotation may be imparted to the cleaning brush.

The constructional features of our invention 20 will now be described, and the novelty thereof pointed out in the appended claims.

In the accompanying drawing:

Figure 1 is a vertical sectional view of 25 the irregular line 1—1, Fig. 2, looking in the direction of the arrows, and showing very clearly the construction of our invention.

Fig. 2 is a view on the line 2—2, Fig. 1, looking in the direction of the arrows, the 30 view being broken out to show the gear connection and ratio.

In the drawing, the numeral 10 indicates 35 a common spigot connected with the source of domestic water supply, in which the main pressure is relatively constant.

Our attachment comprises a casing 11 recessed at one side and covered by a plate 12. The proportions of the parts 11 and 40 12 are best indicated in Fig. 2, from which it will be seen that the casing 11 and 12 is of general circular order, and provided with a projecting portion 13, by means of which it may be connected to the spigot in a manner which presently will be described.

45 A shaft 14 is journaled in a transversely bored embossment 15, on the plate 12, and has a bearing at its other end in a step formed in a like embossment 16 on the frame 11. The projecting end of the shaft 14 has 50 attached thereto a crank 17. Keyed to the shaft and located within the recess in the frame 11, is a multiplying gear 18, the said gear engaging a pinion 19 keyed upon a shaft 20, which latter is suitably journaled 55 in the frame 11 and the covering plate 12.

The shaft 20 extends oppositely from the crank 17, and its outer end has connected thereto a radial cleaning brush 21, adapted to be received inside of a bottle by passing the bottle thereover, in a manner which 60 will be understood.

The projecting portion 13 of the casing is bored for the reception of the threaded end of the neck 22 of a union, the collar 23 of which is adapted to be screwed upon the 65 outlet end of the spigot 10. A gasket 24 may be employed to seal the connection with the spigot.

The casing 11 is provided with a small lateral opening leading into the bore in the 70 projection 13, near the end of the neck 22 of the union. One end of a small tube 25 is fixed in the said opening and is bent downwardly to bring its free end into parallelism with and to lie closely adjacent to the shaft 75 20, so that the neck of a bottle may receive both the shaft 20 and the tube 25. It is preferable that the free end of the tube 25 be extended for a considerable distance along the shaft 20, so as to enter the bottle. 80

When a bottle is passed over the brush and made to embrace both the shaft 20 and the tube 25, and the spigot is opened to the flow of water, the pressure upon the latter will cause the ejection of water through the tube 85 25 into the bottle with unusual force, by reason of the constricted outlet formed by the tube 25. Notwithstanding the presence of the brush, the water is made to strike the remoter end of the bottle with considerable 90 force. The level of water maintained by arranging the bottle in horizontal position, aided by the constant flow, provides a supply sufficient at all times to effectively cleanse the bottle. By rotating the crank 17, a very 95 rapid rotation is imparted to the brush 21 through the multiplying gears, and every portion of the interior of the bottle is swept by the brush and the water and thoroughly cleansed. 100

A gland 26 may be applied to the shaft 20 at the point where it leaves the frame 11, to exclude the water from working into the operating mechanism. The recess in the frame 11 may be packed with oil or grease, 105 before the cover plate 12 is secured in place, and efficient lubrication thereby assured.

The cavity formed by the bore in the extension 13, has no outlet other than the duct 25, so that the full force of the main pres- 110

sure is exerted in ejecting the stream of water.

Having thus described our invention, what we claim and desire to secure by Letters Patent of the United States, is:

1. In a bottle washing device, a casing, a shaft rotatably mounted in said casing, a brush carried by the said shaft, means for rotating the said shaft, the said casing being provided with a bored extension separated from the interior thereof, means for connecting the bored extension with a source of water supply, and a small duct leading from the bored extension to the brush and adapted to enter a bottle when placed over the brush.

2. In a bottle washing device, a recessed casing, a shaft rotatably mounted in the casing, a gear on the shaft within the recess of the casing to effect rotation of the shaft, and a brush carried by the said shaft, the said casing being provided with a bore separated from the recess for connection with a water supply, and a duct independent of the shaft leading from the bore to supply water to the brush and adapted to enter a bottle when placed over the brush. 20 25

In testimony whereof, we have signed our names at Milwaukee, this 24th day of April, 1926.

EUGENE E. EDENHARDER.
JACOB E. EDENHARDER.
